UNITED STATES PATENT OFFICE.

HENRY C. SAMPLE AND FRANZ RABL, OF PHILADELPHIA, PENNSYLVANIA.

ELECTRIC LAMP.

SPECIFICATION forming part of Letters Patent No. 248,111, dated October 11, 1881.

Application filed February 14, 1881. (No model.)

To all whom it may concern:

Be it known that we, HENRY C. SAMPLE and FRANZ RABL, both of the city and county of Philadelphia, and State of Pennsylvania, have invented an Improvement in Electric Lamps, of which the following is a specification.

Our invention has reference to electric lamps in which the luminosity is effected by the voltaic arc, and in which the carbons are fed in a vertical direction; and it consists in providing a second electro-magnet or shunt-magnet and locating the same under the carbon-operating armature, said electro-magnet or shunt being continually traversed by a current of electricity for the purpose of causing the downward action of the armature to take place more rapidly and positively; further, in a poised armature to operate the positive carbon, said armature being poised between two electro-magnets; further, in providing a conducting-follower to follow the point of the descending carbon; further, in the construction of the clamping device for the lower carbon, whereby the same may be clamped and adjusted entirely from the outside; further, in so constructing the lamp that it can be readily changed from a traveling light to a center light, and vice versa, all of which is more fully set forth in the following specification, and shown in the accompanying drawings, which form part thereof.

Heretofore in lamps of this class in which the upper or positive carbon is automatically fed downward by gravity governed by the force of the electro-magnet, which, in turn, is controlled by the condition of the voltaic arc, one of the great defects lay in the fact that the moment the distance between the two poles of the carbons became too great for the passage of the current the armature actuating the upper carbon did not free it sufficiently in the short period of time required to prevent flickering.

In all lamps heretofore constructed the lower or negative carbon has been secured inside the lamp, and in many cases required the removal of the globe, and in no case have they been constructed so that a fresh carbon point could be inserted, adjusted, and clamped from the outside of the lamp.

Another objection to the lamps of this class

has been that there was as much as from five (5) to twenty (20) ohms difference in the resistance—a most objectionable feature to traveling light lamps—and this is caused by the varying lengths of carbon, due to disintegration in burning, over which the electric current has to pass to reach the electrode, the positive carbon, and from the negative electrode to the metal frame. Endeavors have been made to overcome this by plating the carbons, but this is not satisfactory, owing to the fact that the coating is never perfect. In lamps as heretofore constructed it has been impossible to change them from traveling light to a center light without the removal, substitution, and addition of many parts, and in no case have they been made that the change could be made by any novice or a person unacquainted with the theory of the electric lamp by simply following a few directions and without materially changing the construction of said lamp.

It has been our object to overcome all of the above objectionable features in lamps of this class, and the manner in which we accomplish this result will be more fully set forth herein-after.

In the drawings, Figure 1 is a perspective view of the armature to operate the upper carbon. Fig. 2 is a sectional plan of our improved lamp on line $x-x$ of Fig. 3. Fig. 3 is a side elevation of same, with the casing inclosing regulator and lower carbon-holder in section.

A is the box to contain the mechanism to control the movement of the carbons.

B is the frame of the lamp, and holds the globe and lower carbon, and is insulated at c from the box A.

C is the clamping device at the bottom of the frame B, for clamping the lower carbon. It consists of a solid part, D, provided with a conical screw-thread, into which screws a screw-cone, E, having clamping-jaws on the end, and a shank having a milled head or hand-wheel, F, extending below the frame. The carbon G passes through the piece E, which it fits very loosely, but may be clamped therein by causing the split ends of the cone to be pressed together by screwing the screw-cone E into the conical socket D. The reverse construction may be used, if desired.

The upper carbon, K, is narrowed at the top,

and is inserted into the socket of rod J, which works freely through holes I in box A, and is used to allow all of the carbon pencil to be burned. The diameters of the carbon and rod 5 are the same. The carbon K is guided vertically by rollers L, two of which are carried in a frame, L', supported by pin N, and pressed against the carbon by spring O. The two upper rollers L are directly opposite, and the lower roller L is opposite the regulating-armature. The armature Q is pivoted at r to supporting-rod T, and is provided with a pressure-spring, t, and the armature is furnished with a projecting piece, R, the end of which is 10 curved to the radius of the carbon K and rod J. The spring t keeps the projection R against the carbon with a gentle pressure, yet allowing it to readily free itself when necessary. A light spring, q, holds the armature down when 15 the magnets P are demagnetized. However, in our improved construction it is not absolutely necessary. Situated above the armature are electro-magnets P, and located below the same are one or more electro-magnets or shunt-magnets, U. When the current is passing, the armature is poised between the poles of the upper and lower magnets, the upper magnets, P, having the greater strength, as they must support the weight of the carbon G and its rod J. The 20 electro-magnets or shunt-magnets U are wound with very fine wire. The electro-magnets P are wound with large wire, one end of which is connected with the position-screw cup Z by wire e, and the other end of which is secured 25 to the box A. The wire e is tapped by wire f, which communicates with the coil of the shunt-magnets U, the other end of which is connected with the frame B by wire h. By this construction a small part of the current is always passing 30 through the shunt-magnet; hence the armature Q is continually attracted in both directions, causing the carbon to be balanced and its movements governed by the difference between the varying power of the upper and the power 35 of the lower magnets. The negative wire is connected with the frame B by the screw-cup Z'.

Encircling the upper carbon, K, is a weight-follower, V, which is electrically connected with the carbon by springs d. This follower V is 40 hung from conducting-cord W, made of very fine copper wires, which pass through hole k in box A, and are wound upon the drum M, attached to the lower wheel, L, and carried in frame L'. The pin l causes the metallic cord 45 to be wound up uniformly upon the drum. A non-conducting cord, m, is also connected to the drum M, and passes over the idler-rollers S S' S'', and is connected with the lower carbon-cap, g.

50 Secured to the box A is an adjustable spring, X, which may press against the upper carbon, and to the frame B is secured an adjustable spring, X', which may press against the lower carbon. Also secured to the bottom of the box 55 A are spring-catches b b, which support the follower V when not in use.

The operation is as follows: To use the lamp as a traveling light, throw the springs X X' around, as indicated in full lines, and disconnect the cord m. The current passing through both upper and lower magnets, the armature is balanced and the current passes down the conducting-cord W to weight-follower V, and is conducted to the carbon by springs d near the point or electrode of the carbons, thereby 60 overcoming the great resistance which would be the result of causing the current to pass down the carbon. As the carbon burns down it is lowered to follow the negative electrode of the lower carbon, and as it burns itself the 65 lowering movement is much increased. If the drum M is one-half the diameter of the wheel L to which it is secured, the follower V will descend one-half as fast as the carbon descends; but as the upper carbon burns twice as fast as 70 the lower carbon, this will keep the follower always at the same distance from the positive electrode of the carbon. Should the electrodes be too far apart, the current ceases to traverse the electro-magnets P, but not so in the case 75 of the shunt-magnet U; hence the armature is instantly pulled down, which movement may be accelerated by the spring q, and causes the upper carbon to be forced downward and finally freed, when the voltaic arc is made and the 80 magnets P once more electrified, causing the armature to be raised and become once more balanced. This movement raises the carbon 85 until the proper arc is once more made.

To change the lamp from a traveling light 90 to a center light, the conducting-cord W is disconnected and the follower V shoved up until held by the spring-catches b b. The springs X and X' are swung around and rest upon the carbons, as shown in dotted lines, Fig. 3. The 95 cord m is connected with cup g, and the lower-carbon clamps loosened. Now, the lower carbon will be raised by the downward movement of the upper carbon, and in the proportion of one to two; hence, as the upper carbon burns 100 twice as fast as the lower carbon, the voltaic arc will always remain in one spot. The current is conducted to the negative carbon by spring X, and from the positive carbon to frame B by spring X'.

Having now described our invention, what we claim as new, and desire to secure by Letters Patent, is—

1. In an electric lamp, the combination of carbon K, with its rod J, friction-roller L, armature Q, provided with projecting piece R, spring T, spring q, electro-magnets P, shunt-magnets U, lower carbon, G, and means to adjust and clamp said carbon from the outside, as and for the purpose specified.

2. In an electric lamp, the combination of carbon K, with its rod J, friction-roller L, carrying a drum, M, conducting-cord W, follower V, provided with contact-pieces d or their equivalent, armature Q, provided with a projecting piece, R, spring T, spring q, electro-magnets P, shunt-magnets U, lower carbon, G,

and means to clamp said carbon in place, as and for the purpose specified.

3. In an electric lamp, a conducting-follower in contact with the descending carbon, in combination with mechanism to lower both the carbon and follower in such a manner that as the carbon descends and burns the follower will always be at or about the same distance from the point of the upper carbon and lower carbon, substantially as and for the purpose specified.

4. In an electric lamp, the combination of carbon K, roller L, drum M, follower V, conducting-cord W, and mechanism to regulate the downward movement of said carbon, substantially as and for the purpose specified.

5. In an electric lamp, the clamp C for adjusting and clamping the lower carbon wholly from the outside, consisting of the piece D secured to the frame, and provided with a conical screw and cone-piece, E, having a central

aperture through which the carbon passes, or its equivalent clamping-ends, and provided with a downwardly-projecting shank furnished with a milled head or its equivalent, located wholly on the outside of the lamp, substantially as and for the purpose specified.

6. In an electric lamp, the combination of electro-magnets P in circuit with carbons, shunt-magnet U out of circuit with carbons, poised armature Q, provided with projecting piece R, friction-roller L, drum M, conducting-cord W, follower V, carbons K and G, frame B, box A, and clamp C, substantially as and for the purpose specified.

In testimony of which invention we hereunto set our hands.
